UNITED STATES PATENT OFFICE

163,570

COMBINATION HOLDING DEVICE FOR
HANDBAGS AND GLOVES

Arthur C. Cimaglia, Chicago, Ill., assignor to Mi-Lady Specialties, Inc., Chicago, Ill., a corporation of Illinois

Application August 18, 1950, Serial No. 11,832

Term of patent 14 years

(Cl. D87—2)

To all whom it may concern:

Be it known that I, Arthur C. Cimaglia, a citizen of the United States, residing in Chicago, in the county of Cook, and the State of Illinois, have invented a new, original, and ornamental Design for a Combination Holding Device for Handbags and Gloves, of which the following is a specification, reference being had to the accompanying drawing, forming a part thereof, in which

Fig. 1 is a perspective view of a combination holding device for handbags and gloves, illustrating the device in position for holding a handbag, and

Fig. 2 is a side elevational view of the device in position for holding gloves.

I claim:

The ornamental design for a combination holding device for handbags and gloves, substantially as shown and described.

ARTHUR C. CIMAGLIA.
